UNITED STATES PATENT OFFICE

2,279,619

DISH WASHING MACHINE

Herbert H. Fisher, San Francisco, Calif.

Application September 3, 1940, Serial No. 355,117

4 Claims. (Cl. 141—9)

This invention relates to dish washing machines and more particularly to closures therefor.

Among the objects of the invention is to provide improved means for closing the splash compartment of dish washing machines.

Another object is to instantly stop the water splashing mechanism when a compartment door is opened.

Another object is to provide improved means for admitting water and injecting soap into the washing tray.

Other objects and advantages will appear as the description progresses.

In this specification and the accompanying drawing the invention is disclosed in its preferred form. But it is to be understood that it is not limited to this form, because it may be embodied in modifications within the spirit of the invention as defined in the claims following the description.

In the one sheet of drawings:

Fig. 1 is a front elevation of a dish washing machine constructed in accordance with this invention. The water tray is shown in vertical section on the line 1—1, Fig. 2.

Fig. 2 is a side elevation of the same, showing one door of the closure open.

Fig. 3 is a wiring diagram of the motor circuit having the safety stop switches interposed therein.

In detail the construction illustrated in the drawing, referring first to Fig. 1, includes the water tray 1, adapted to be mounted upon a bench, table or any form of supporting stand, not shown. This tray has the bottom 2, sides 3, 4 and the front and back 5, 6, surrounded by the top flange 7. It is preferably formed of an integral casting for stability and tapers from top to bottom, except at the sides where the recesses 8, 9 are formed to clear the lower edges of the closed doors.

The sump 10 is attached to the bottom of the tray and has a strainer and the elevated overflow pipe 11. The sump is connected to the sewer or other outlet. The top of the over flow pipe is adapted to maintain a definite water level 12 in the tray.

The centrifugal pump 13 is fixed to the bottom of the tray and discharges through the coupling 14 within the tray. The pump is driven by the motor 15 mounted upon the bracket 16 attached to the tray. The rotary distributor head 17 is mounted upon the discharge pipe of the pump within the packing coupling 14. The discharge

openings such as 18 are provided on opposite sides of the center of rotation and set at an angle to the plane of rotation to cause the head to rotate when water is forcibly pumped therethrough. The splash heads 19, 20 are similarly constructed and swiveled in the opposite ends of the distributor head 17. The rotation of the distributor head 17 rotates the splash heads 19, 20. The water within the tray flows back from the sump 10, through the screen therein, to the intake of the pump 13 for rapid redistribution of the water at high velocity beneath the dish rack.

The dish rack is conventional and consists of a box like structure 21, having an open bottom formed by the cross rods such as 22, to hold dishes stacked on edge therein. This rack slides in the angular guides 23, 24 fixed on the top flange 1 of the tray, for placement and removal from either side of the machine.

Pivot brackets such as 25, 26 are fixed to the flange 1 on opposite sides of the tray adjacent to the recesses 8, 9. The water service pipe 27 extends up through the bracket 26 and has the self-closing valve 28 fixed thereon with the side outlet coupling 29, discharging through the pipe 28', into the pump 13.

The liquid soap pump 30 is mounted upon the opposite bracket 25 and has the outlet pipe 31, thereon, which is alined with the outlet coupling 29 on the opposite side of the tray. These opposed outlets form the fixed pivots for the telescoping closure doors of the machine.

This closure consists of two segmental doors having the respective side plates 32, 33 and 34, 35. These doors are completed by the tops 36, 37 telescoping one within the other and joined to their respective side plates 32—35. The radii of these doors are struck from the common axis of the outlet coupling 29, and the outlet pipe 31 upon which they pivot freely. The outer edges of each door are provided with rubber bumpers such as 38 and 39 respectively, that rest upon the flange 1 when the doors are closed within the top opening of the tray 1. When closed the inner edges of the doors overlap. Thus assembled the splash of soapy water within the tray and the closure is retained and drains back into the tray.

After the dishes are thoroughly washed with the soapy water the overflow 11 is lifted and the tray is drained and the accumulations in the sump screen disposed of. Then rinsing water is admitted through the valve 28 and the operation repeated. Meantime clean water is admitted

until all the accumulation from the dishes overflows or descends into the sump 10.

To rinse the tops of the dishes in the rack 21 the top spray 40 is provided. It is connected directly to the valve outlet coupling 29 and discharges above and within the closure.

Each of the doors is provided with the side trips 42, 43, see Fig. 2, to depress the spring actuated dielectric rods 44, 45, of the respective stop switches 46, 47 mounted on the sides of the tray. When either door is lifted the corresponding switch snaps open, see Fig. 3, which opens the motor circuit and stops the pump to prevent splash of water through the open door. Since the water is scalding hot and soapy there is danger to the operator, or possible property damage without these precautionary stop switches 46, 47.

In the motor circuit shown in Fig. 3, the current flows in over the wire 48, across the main switch 49, the motor 15, the two stop switches 46, 47, and back over the wire 51, to the source of power. When either door is opened the corresponding switch 46, 47 automatically opens to break the circuit and stop the motor and the water distributing assembly driven thereby.

Having thus described this invention what is claimed and desired to be secured by Letters Patent is:

1. A dish washing machine having a tray with water distributing means therein; a motor actuating said distributing means; a pair of telescoping doors pivoted on a common horizontal axis

on said tray; and means actuated by said doors for automatically stopping said motor when either of said doors is opened.

2. A dish washing machine having a tray with water distributing means therein; a motor actuating said distributing means; a water valve having an outlet coupling extending into said tray; a pivot on said tray opposite said outlet coupling; a door pivoted on said pivot and said outlet coupling; and means for automatically stopping said motor when said door is opened.

3. A dish washing machine having a tray with water distributing means therein; a water outlet coupling and a soap outlet pipe aligned on opposite sides of said tray; a pair of telescoping doors pivoted on said outlet coupling and outlet pipe; and means for automatically stopping said water distributing means when either of said doors is opened.

4. A dish washing machine having a tray with water distributing means therein; a motor actuating said distributing means; a water valve having an outlet coupling extending into said tray; a soap outlet pipe on said tray aligned with said water outlet coupling; a pair of telescoping doors pivoted on said outlet coupling and outlet pipe; stop switches on said tray in operative relation to said doors respectively; an electric circuit including said motor and said switches therein; whereby said motor is stopped or started when said doors are opened or closed respectively.

HERBERT H. FISHER.
